E. N. Porter

United States Patent Office.

E. N. PORTER, OF MORRISVILLE, VERMONT.

Letters Patent No. 63,294, dated March 26, 1867.

IMPROVED MOP SQUEEZER.

The Schedule referred to in these Letters Patent and making part of the same.

TO ALL WHOM IT MAY CONCERN:

Be it known that I, E. N. PORTER, of Morrisville, Lamoille county, State of Vermont, have invented new and useful improvements in Mop Squeezers; and I do hereby declare the following to be an exact description thereof, reference being had to the accompanying drawings, and to the letters of reference marked thereon, making a part of this specification, in which—

Figure 1 is a sectional view.

Figure 2, a top view.

The nature of my invention consists in the jaws D, lever H, and treadle J, arranged and operated in combination with the movable platform B. I construct the mop squeezer separate from the pail, and not fastened to the pail; the jaws of the mop squeezer being attached to a movable platform, and the jaws formed of slats with spaces between the slats, operated by a treadle; the platform resting on casters, and the pail merely set on the platform so as to be easily moved across a room without requiring the lifting and moving of a heavy mop squeezer as commonly attached to the pail.

A represents the movable pail that contains water for dipping the mop in; B the platform, upon which the pail is placed; C the casters; D D the jaws or squeezer, that presses the mop, made of slats E E, one jaw being stationary and firmly attached to the uprights or standards G; the other jaw D being movable, and operated by the lever H and treadle J.

What I claim as my invention, and desire to secure by Letters Patent, is—

The jaws D, lever H, and treadle J, arranged and operated as herein described, in combination with the movable platform B, for the purpose set forth.

E. N. PORTER.
